SHEET COLLATOR

Albert Dager, Los Angeles, Calif.

Application September 17, 1945, Serial No. 616,713

6 Claims. (Cl. 270—58)

1

The present invention relates to collators, and has for an object the provision of a collator adapted for use in printing or binding establishments, which utilizes little space, is readily moved from place to place in the shop, is of few parts and which is capable of manifolding multiple sheets rapidly and accurately.

At the present time it is customary to manifold sheets by hand or on large machines which are very expensive and beyond the means of the average printer. The present invention may be manufactured and sold at a comparatively low figure, is capable of manifolding a number of sheets, as well as placing divider sheets between the manifolded sets, depending on the number of manifolded sheets to a book.

An object of the invention is the provision of a collator which has its parts so arranged as to positively assure a proper and accurate manifolding operation.

Another object is the provision in a collator of means which prevents the gathering of incomplete sets in the event that the sheets are not properly manifolded.

Another object is the provision in a collator of a simple and inexpensive means for stacking collateral sheets in a receiving bin.

Another object of the invention is to so relate the various instrumentalities entering into the machine as to minimize inertia of moving parts.

A further object is the provision of a simple means, readily regulated by an operator, to control the insertion of a divider sheet after a selected number of sets has been manifolded.

Another object of the invention is the provision in a collator of means for depositing manifolded sheets in a bin and in a properly stacked relationship.

Another object is the provision of new and improved means for raising sheets from a supply bin and for delivering said sheets properly manifolded into a receiving bin.

Another object is the provision in a collator of various instrumentalities for collating or manifolding sheets and in which the parts are readily accessible for adjustment, repair and the like.

With the above mentioned and other objects in view, the invention consists in the novel and useful provision, formation, construction, association and relative arrangement of parts, members and features, all as shown in certain embodiments in the accompanying drawings, described generally and more particularly pointed out in the claims.

In the drawings:

2

Fig. 1 is a side elevation of the collator;

Fig. 2 is a top plan view of the collator shown in Fig. 1;

Fig. 3 is a fragmentary side elevation of certain portions of the collator and shown on an enlarged scale from that of Fig. 1;

Fig. 4 is a fragmentary cross sectional detail on the line 4—4 of Fig. 3;

Fig. 5 is a fragmentary sectional view on the line 5—5 of Fig. 3;

Fig. 6 is a fragmentary sectional view on the line 6—6 of Fig. 5;

Fig. 7 is a fragmentary detail illustrating a changed position of certain of the parts of the machine from a like portion shown in Fig. 3;

Fig. 8 is a fragmentary elevation of means for driving the conveyor belts of the collator;

Fig. 9 is an end elevation of the means shown in Fig. 8;

Fig. 10 is an enlarged view, partly in section, of suction feet for lifting paper to be manifolded;

Fig. 11 is a fragmentary detail of means for atmospherizing the suction feet;

Fig. 12 is a fragmentary side elevation of elevator means for delivering sheets in manifolded order from the conveyor belts to a receiving bin;

Fig. 13 is a sectional view on the line 13—13 of Fig. 12;

Fig. 14 is a fragmentary elevation of means for controlling the insertion of divider sheets during a collating operation;

Fig. 15 is a fragmentary, partially sectional view of counting mechanism which controls the insertion of a divider sheet between a preselected number of manifolded sheets;

Fig. 16 is a fragmentary and partially sectional view on the line 16—16 of Fig. 15;

Fig. 17 is a fragmentary sectional view on the line 17—17 of Fig. 15; and,

Fig. 18 is a wiring diagram of circuits employed in the present invention.

Briefly, the present collator contemplates a series of racks or bins within which are placed stacks of sheets which are to be collated. By collation I mean sheets which are to be manifolded; thus I may have two, three or any multiple number of bins, and sheets of various colors, weight or size may be placed in the bins, such as for instance white, blue, yellow, etc. Each bin has a stack of said sheets. Order books and the like often use sheets which have been manifolded, and as the manifolding of many sheets by hand is most tedious and expensive the present machine offers the binder and printer a device within his means and which will do the manifolding in a

satisfactory manner. Initially the machine provides bins within which, as stated, are placed the stacks of sheets to be manifolded. I provide means such as suction feet, connected with a suitable pump, which do not swing on an arc but are raised and lowered in a given plane. The suction feet, when suction is applied individually, lift the sheets from the stacks. I provide a system of conveyors, one conveyor for each bin, adapted to move toward the sheet which has been raised by a suction foot, to receive said sheet, and deposit the same in a receiving bin. As suction feet may not always properly lift the sheets, due to irregular stack conditions of paper, I have provided a novel means which renders manifolding impossible when for any reason the sheets fail to be lifted properly by the suction feet.

In the present invention I have provided two means for assuring a proper manifolding operation. If for any reason a suction foot fails to properly lift one of the sheets from a stack, the vacuum to all of the suction feet is bled through a valve, and the means which causes reciprocatory travels of the conveyors is rendered inoperative.

When manifolding, it is customary after a given number of sets has been stacked, to place a divider sheet upon the top of the stack. This divider sheet functions to indicate the number of manifolded sets in the stack and likewise may indicate a desired size for a book. To accomplish this, I have provided a novel means which may be pre-set to place a divider sheet upon or underneath a stack of manifolded sheets.

Referring to the drawings and specifically to Figs. 1 and 2, I have provided a frame 1, which supports by means of posts 2, bins 3. In the showing there are three bins, arranged at different levels, as indicated at 4, 5 and 6. Adjustable slides, designated generally as 7, are provided for each bin platform 8, and a pair of spaced apart angle members 9 and 10 engage the side and front edge of a stack of sheets 11 in a bin. These angle members may be adjustable as to spacing therebetween so as to accommodate for different widths of sheets. The uppermost bin may have sheets of white color, the next bin therebelow a stack of sheets 12, yellow in color, and the following bin a stack 13 of blue color. The bins are staggered in arrangement, as shown in Fig. 1, the lowermost bin being forward of the next bin thereabove, and so on. Such an arrangement prevails regardless of the number of ascendingly related bins.

The frame 1 is so constructed as to properly relate each bin to means adapted to remove sheets from the bins. Thus the posts 2 are mounted on the portion 14 of the frame, said portion 14 being bent to provide a vertical portion 15, followed by a horizontal portion 16 substantially parallel to portion 14. Immediately below the frame part 16 and mounted upon a suitable foundation are a pair of pedestals 17 and 18, and journaled in said pedestals is a shaft 19. The shaft 19 carries a pair of cams 20 and 21. Suitable means, designated generally as 22, rotates shaft 19. This means 22 may comprise a motor 23, which drives a reduction gearing indicated by the square 24, which in turn drives shaft 25, and suitable gearing not shown in turn furnishes the drive between shafts 19 and 25.

The cam 20 is adapted to actuate the means for raising the sheets from the several bins. This means, designated as an entirety by 26, includes an elevator bar 27 the lowermost end of which

carries a wheel or roller 28 for contact with the edge of cam 20. The said bar is provided with a longitudinal slot 29 within which is positioned a lug or tongue 30. Said lug or tongue is adjustably attached to bracket 31, see Fig. 3, the said bracket in turn being fastened by a suitable means 32 to the framing portion 15. The elevator bar is actuated by the cam 20, and the direction of bar movement is controlled by the lug or tongue 30.

The elevator bar carries one or more arms 34, the number of arms depending upon the number of bins. Each arm 34 is pivotally mounted by means 35 to the bar 27, see Fig. 7, and the angularity to be assumed by the arm relative to the elevator bar is controlled by adjustment means 36. This adjustment means includes an angular bracket 37, carrying a screw 38; one end of the screw engages the arm at some distance from the pivot point 35. The uppermost end of said arm carries a foot 39, commonly called a suction foot for the reason that the foot is adapted to communicate with a vacuum pump whereby when the foot is under sub-atmospheric pressure and is brought into contact with the uppermost sheet of a stack in one of the bins, the sheet is lifted, as shown in Fig. 7, and as hereinafter more fully detailed. While I may use single suction feet for each bin, yet in the present instance I have found it more expedient to use pairs of such feet. Thus, referring to Figs. 2 and 10, each arm 34 at its outermost end carries a transverse tube 40, and mounted on said tube are suction feet, one of which has heretofore been designated as 39, and the second of which, see Fig. 10, is designated 41. Each suction foot is provided with a transverse bore 42, in communication with tube 40, and with a bore 43 in communication with bore 42 and at an angle thereto. The suction foot may be secured to the tube 40 in any approved manner such as by screwthreading, as indicated at 44. A pipe 45 communicates through flexible tubing 46 with a connection 47 on arm 34, the connection in turn is secured to a tube 48 leading to the suction foot 39 and tube 40. Pipe 45 connects with a pump 49, such as a vacuum pump. When the cam 20 is being rotated it is evident that the cam will progressively raise and lower the elevator bar 27 in such a manner as to bring the aligned pairs of suction feet, as indicated at 39 and 41, into engagement with the uppermost sheet of a stack in one of the supply bins. If there is reduced pressure in the line leading to said feet, said feet will lift the sheet, or a portion thereof, upwardly, as shown in Fig. 7.

After pairs of suction feet have descended upon the uppermost sheet of several stacks of sheets and lifted the same, it is essential to remove the sheet and at the same time break the vacuum to the suction feet. To remove the sheets and deposit the same in the receiving bin, I have provided a plurality of belts. These belts are adapted to be arranged in pairs and in such a manner that two of the courses are parallel and in juxtaposition. The belts are suitably carried by a framing designated generally as 50. This framing includes two members 51 and 52, both provided with a base member 53 carrying front and rear wheels 54 running on a trackway 55, secured to framing member 16. Front and rear uprights 56 and 57 are secured to the base member 53. Extending between the framing members 51 and 52, and specifically the uprights 56 and 57 thereof, are a plurality of front and rear shafts 58 and 59. The arrangement is such that there are pairs of said

shafts for each bin. By way of example, the uppermost bin 9 has a pair of closely related shafts 58, as indicated at 60 and 61, for uprights 57, and a like pair of shafts secured to the uprights 56, as shown at 62 and 63. Carried on the shafts 62 and 63 are a plurality of spaced apart pulleys 64 and 65, and carried on shafts 60 and 61 are a plurality of pulleys 66 and 67. Passed between the pulleys 64 and 66 are continuous belts 68, and between pulleys 65 and 67 are continuous belts 69. It is to be observed that courses of said belts, as indicated at 70 and 71, are contiguous. The frame 50 for the belts is adapted to be reciprocated as to movement so as to approach the bins when sheets are being raised by the suction feet, and to receive the said sheets between pairs of said contiguous belts, when the vacuum to said feet is broken.

To reciprocate the said frame 50, means detailed in Fig. 3 is utilized. This means includes an arm 72 intermediately pivoted at 73 to a bracket 74, the bracket being secured to frame portion 15; one end of said arm carries a roller 75 in engagement with the edge of cam 21, see Fig. 6, while the opposite end of said arm is pivoted to a link 76, the link in turn being secured at 77 to a lock bar 78. The lock bar is held by means 79 to the framing portion 16 in such a manner as to permit the said bar to be reciprocated. The lock bar is provided with a notch 80. The framing 50 carries a solenoid switch 81, the plunger 82 of which is adapted to be received within the notch 80 when the solenoid is not actuated to lift said element. This forms a releasable connection between the lock bar 78 and the framing 50, so that normally the cam 21 when rotated will reciprocate the framing. One or more coil springs 83 are secured between framing 50 and the framing portion 16 to normally urge said framing 50 in one direction. Thus the cam 21 in its rotation works against the tension of said spring or springs 83.

To properly deliver the sheets to a receiving bin in manifolded order, chutes 84 are provided at the discharge end of each pair of belts. These chutes may include downwardly disposed and transversely extending metal pieces carried between the uprights 56 and so positioned as to direct paper downwardly as it is discharged between the two courses 70 and 71 of a pair of belts. No particular means is illustrated for supporting the said chutes other than the use of transverse bars which are attached between the members 56; and the transverse edge of said chutes adjacent the discharge portion for the belts is normally positioned above the plane of the belt courses 70 and 71, so that paper when discharged from between said belts engages the under surface of a chute. Each member 56 is provided with an outstanding bracket 85, between which extends a pair of shafts 86 and 87. Carried between the pair of members 56 and beneath the lowermost shaft for a pair of conveyor belt members is shaft 88. Shafts 87 and 88 carry spaced apart pulleys 89 and 90 respectively, between which pulleys are continuous belts 91. Shaft 86 carries one or more pulleys 92, and shaft 59 is provided with one or more pulleys 93 in alignment with the pulleys 92, between which pulleys extend continuous belts 94. It is intended that paper during a manifolding operation should be directed by the chutes between two courses of the belts 91 and 94, the said belts in turn direct the paper into a receiving bin 95. This receiving bin includes a platform 96 provided on opposite edges with guides

97. The guides 97 move longitudinally of a pair of supporting legs 98, to the end that the said platform may lower as sheets are received thereon. The said legs 98 form a part of the framing 1. The framing members 16 extend downwardly at 99, and this portion is adapted to carry means for assuring that the paper will be properly stacked in the receiving bin. This means includes a lever 100, swingingly mounted on a shaft 101 which extends between framing portions 99. The lever is provided with an angle piece 102, adapted to contact a transverse stop member 103 secured to the framing portions 99 to limit downward swing of the lever 100. Carried on a shaft 101 and upon opposite sides of the lever 100 are a pair of pulleys 104 and 105. The outermost end of lever 100 carries a transversely positioned shaft 106, and mounted on said shaft are a pair of pulleys 107 and 108. Continuous belts 109 and 110 are passed respectively around the pulleys 105 and 107 and pulleys 104 and 108. The lever 100 carries a finger piece 111, whereby the device may be swung about shaft 101. The belts on this device are positively driven by means of a pulley 112 attached to one end of the shaft 101. The pulley in turn is driven by a continuous belt 113 communicating with a suitable drive means.

To assure that the manifolded paper in the receiving bin is properly aligned, it is stacked by what is known as a "jogger" 114, consisting of two members of identical construction, one for each side of the framing portions 99; for that reason one "jogger" will be described, the same numbers of reference applying to the other. The jogger includes a pair of bent levers 115, pivoted at 116 to the frame; one end of said lever is pivoted at 117 to an elongated leaf 118, the said leaf having a depth sufficient to contact the receiving bin at its highest position. A link 119 is secured between the framing and the leaf 118. An arm 120 is pivoted at 121 to the outermost end of lever 115. Lever 120 has a bent end extremity 122, which overlies the framing portion 16. A coil spring 123 interconnects the outermost end of lever 115 and the framing. Thus the tendency is to revolve both the lever 115 and the link 119 to move the leaf 118 against the side edges of the manifolded sheets. However, the arrangement is such that the bend end 122 of arm 120 is engaged by the framing 50 during its movement so as to swing the "jogger" away from the manifolded sheets and then allow the "jogger" to strike the manifolded sheets under spring tension.

Reference is made to Figs. 8 and 9 which illustrate one means whereby the conveyor belts 68 and 69 may be driven. This means includes a shaft 124 mounted in suitable bearings 125, 126 and 127 attached to one of the posts 57 of frame 50. The shaft carries bevel gears 128, 129 and 130, which bevel gears mesh with further bevel gears 131 and 133 inclusive, secured to shafts 61. A flexible cable 134 connects with shaft 124 and with the motor 23. The uppermost continuous belt of each pair may be turned by mere friction, due to the presence of a sheet between the courses 70 and 71, or as an alternative, intermeshing gears may be provided between the rollers to render the drive a positive one.

So far I have described a means which will lift individual sheets from supply bins for delivery between conveyor belts, which in turn deliver the paper in a manifolded or collated relationship within a receiving bin. It is a known

fact however that a mechanism does not always function as intended, and I therefore provide certain means for insuring against faulty operation of the machine. I provide means for immediately preventing a collating operation of the machine in the event that the suction feet do not correctly and completely pick up paper for delivery between the conveyor belts. This means is illustrated in Fig. 10 and operates in conjunction with the magnetic switch shown in Fig. 3. One of the suction feet carried by tubular arm 40 is provided with an electrical switch 135; said switch includes a strap 136 secured to but insulated from the suction foot at 137. This strap is provided with a bent end extremity 138. The suction foot is provided with a bore 139 communicating with bore 42, and confined within bore 139 is a stud 140. The shank 141 of the stud is passed through said bore, and a head 142 on said shank may engage the end 138 when urged into such engagement by means of a coil spring 143 included between the head and the body of the suction foot. A wire 144 connects with strap 136, and the suction foot is grounded (as indicated) to the frame of the machine as an entirety to provide the other lead. The ground connection and wire 144 in turn communicate with a suitable source of current supply and with magnetic switch 81. Reference is made to Fig. 18, wherein are shown three of the switches 135 with leads 145, indicative of the ground circuit, while the other leads are representative of lead 144; all of the leads 144 are in circuit with the coil of the magnetic switch 81 and with the source of current supply, indicated at 146. When vacuum is established in the line 45 leading to the suction feet and sheets are engaged by said feet, the studs 140 are drawn inwardly, compressing springs 143, which movement breaks contact between the studs and the straps 136. If, however, a suction foot should fail to lift a sheet, the suction foot is atmospherized, which releases the stud and allows the head 142 to contact member 138 to complete a circuit through the magnetic switch 81. Such action immediately raises the plunger 82 and releases the bar 78, with the result that the carriage 50 does not reciprocate on the frame 16. Upon reestablishment of the system the electric switch will again permit the plunger 82 to be received within the slot 80 of the lock bar, to the end that the conveyor frame may be reciprocated.

When the suction feet lift the paper from the bins it is essential that at the moment the conveyor carriage moves forwardly to receive the sheets between the conveyor belts, that the vacuum to said suction feet be broken. I accomplish this by a valve 147, see Fig. 11. The valve includes a short length pipe 148 which is curved in part and provided with a seat portion 149. This pipe leads to the pipe 45, see Fig. 10. Pipe 148 carries a bracket 150, to which is pivoted at 151 bell-crank lever 152, having arms 153 and 154. Arm 153 swingingly carries a plug 155. The bracket 150 is so formed as to have an angular extension at 156, between which extension and arm 154 is a coil spring 157. This coil spring normally urges the lever into such position as to close the valve, that is to say, the plug 155 to be received on seat 149. One member 57 of the conveyor frame is provided with an angular bracket 158, and an adjustable screw 159 is passed through one arm of said bracket for engagement with portion 154 of lever 152. Thus when the conveyor frame has reached a position adjacent

the supply bins, the screw 159 engages arm 154 and swings the bell-crank lever 152 to raise the plug 155 from its seat, and in so doing atmospherizes the line 45 and bleeds the vacuum to the various pressure feet, thus releasing the paper. The elevator bar 27 is provided with an arm 160, and after the conveyor belts have received the paper therebetween in the manner illustrated for instance in Fig. 7, the elevator bar 27 starts its downward movement due to rotation of the cam 29, and the arm 160 will strike the plug carrying end of arm 153 to seat the plug. It is to be observed that the arrangement of the spring 157 with the lever 152 is such as to provide a toggle. In other words, the valve plug snaps closed to its seat or snaps open.

As the alternate breaking of the vacuum to the suction feet would cause the switch elements to complete a circuit through the solenoid 81 and might disturb proper operation of the conveyor frame by releasing said frame from the lock bar 78, I have provided means whereby when the sheet is properly raised by the vacuum feet the electrical circuit will be broken to the switch 81 just before the vacuum is broken to said feet, and which circuit is immediately reestablished just after the vacuum line is reestablished to said suction feet. Such a means is shown in Fig. 18 and comprises an insulation wheel 161, mounted either on shaft 19 or on an independent shaft 162, in turn driven by motor 23. This insulation wheel is provided with a segmental contact member 163, a brush 164 is adapted to ride on the edge of the wheel and to have engagement with segment 163 during revolution of the wheel. The segment may be grounded to the shaft 162. The said segment and the said brush or wheel 164 are placed in the circuit as illustrated in Fig. 18.

Forming a part of the present invention is means for placing divider sheets under or on a stack of manifolded sheets. This means is illustrated in Figs. 15 to 17 inclusive. The mechanism provides a manually set counter, which will permit any number of sheets to be manifolded at a time, and after a selected number of completed manifold sets has been stacked in the receiving bin, the device will operate to place a divider sheet thereontop. Whereupon manifolding continues until a further divider sheet is required. The counter for this purpose includes a large diameter ratchet wheel 165, mounted on a shaft 166, the teeth of the wheel are numbered, as indicated at 167, starting from a zero indication 168, at which zero indication is placed a projecting pin 169. Mounted on shaft 166 is an arm 170 which may be set at any numbered tooth desired and which arm will actuate mechanism to be hereinafter described so that a divider sheet may be deposited in the receiving bin. Swingingly mounted on shaft 166 is a lever 171, one end of which lever is connected by means of a link 172 to a spring actuated bell crank 173. One arm 174 of the bell crank is in position to be engaged by lug 175, secured to the framing 50; thus each time the framing moves in one direction the bell crank is rocked to in turn move the lever 171 downwardly. Lever 171 pivotally carries a pawl 176, which is adapted to be so actuated as to engage the teeth of the ratchet wheel 165 to revolve the wheel one tooth at a time for each complete reciprocation of the frame 50. When the lug 175 strikes the arm 174 of the bell crank the pawl is revolved about its pivot point to position pawl arm 177 in engagement with a tooth of the ratchet and revolve the ratchet; see dotted lines at 178.

The pawl is urged to the dotted position by an arm 179 which is pivoted at 180 to the framing 1. A coil spring 181 is secured to the arm at one end and made fast to some portion of the framing at its opposite end in such a manner as at all times to urge said arm into engagement with the pawl. Pivoted to the frame at 182 is a lever 183. This lever is normally urged to revolve in one direction by a coil spring 184. This lever is adapted to have trip engagement with lever 185. Lever 185 is pivoted to the frame at 186, and provided with a side extension 187, for engagement with end 188 of lever 183. An arm 189 is pivoted at 190 to the end of lever 185, and said arm is provided with a side extension 191 adapted to contact with one edge of lever 185 to limit downward movement of said arm about its pivot 190. The outermost end of arm 189 is bent at an angle, as shown at 192. This end is adapted to contact, in one position, stud 169. A lever arm 193 is pivoted at 194 to the framing; the short end of said lever has a portion 195 adapted to contact with end portion 196 of arm 183. Lever 185 is normally urged to rotate in one direction by spring 198, to the end that the parts normally and prior to actuation, as stated in the operation, will assume the position shown in Fig. 15. A differential valve 199 includes casing 200, provided with two bores 201 and 202, in substantially right angular relationship, the bore 202 having a greater diameter than bore 201. A valve 203 seats at 204 to close entrance to bore 202. This valve is provided with a valve stem 205 which connects with a depressible head 206, weight of the head unseating the valve. Bore 201 communicates at one end with a tube 207 leading to suction feet, adapted to lift a divider sheet from a bin, while tube 208 is in communication with the pump 49 or main suction line. The long end of the lever 193 is positioned at 197 beneath the valve 203 to hold the valve seated. Thus the suction line has a through passage through the valve casing. In the present instance the shaft 166 is rotated in a direction counter to the rotation made by the pawl, by a spring. The shaft is provided with a pulley 209, about which is wound a cable 210, one end of which cable is connected to a coil spring 211. As shown in Fig. 16, arm 170 has frictional engagement with the hub of the ratchet 165.

In Figs. 12 and 13 I have illustrated a means for receiving sheets from between pairs of conveyor belts and depositing the said sheets in properly manifolded order within a receiving bin. Such a device may be used when a large number of sheets is to be manifolded. Thus in Fig. 12, five sheets may be manifolded, the uppermost pair of belts being utilized for divider sheet purpose. In Fig. 1, three sheets are shown, and in this figure the uppermost bin might hold divider sheets and the other two bins sheets to be manifolded; the use of uppermost bin for divider sheets being optional.

In either case the arrangement which has been described for Fig. 15 would be utilized, and the tube 207 would lead to the uppermost suction feet, while tube 208 has connection with the pump.

The structure of Fig. 12 includes a frame 212, which supports end shafts 213 and 214. Sprockets 215 in spaced pairs are mounted on each shaft; and passed between the upper and lower pairs of said sprockets are continuous chains 216 and 217. The framing 212 is held in any suitable manner, such as by the uprights indicated at 218, to a supporting structure which may constitute

a receiving bin 219. Mounted between the pair of chains are spaced trays 220, each tray transversely extending between the chains and secured at 221, 222 to the links thereof. Immediately above and extending at an angle to each tray is one or more fingers. The spacing between the trays is such as to bring each tray into alignment with the middle course of the pairs of conveyor belts. The trays are mounted so as to have a downward inclination toward the chains, as best illustrated in Fig. 12. Shaft 214 carries either a pulley 224, see Fig. 13, or a sprocket, with means 225 for driving either the pulley or sprocket. The drive means for said shaft includes a clutch indicated at 226, the clutch being known as the one-revolution type. This clutch is adapted to be operated immediately after the conveyor belt frame 50 is moved adjacent the trays to receive sheets from between the said belts, whereupon, when the conveyor belt and frame moves away from said trays, the clutch is operated to move the chains 216 and 217 and carry the six racks, which have just received paper, downwardly for deposit of said paper within the receiving bin 219. The clutch is "thrown out" at this point and the other set of six trays at this time will assume a position for the receiving of additional sheets when the conveyor frame again moves toward said trays. The action of the clutch is of course intermittent and controlled by movement of the conveyor belt frame 50. It is to be realized that the uppermost conveyor belts will not always receive paper, because this particular pair of conveyor belts is used for divider sheets, and divider sheets are controlled by the means shown in Fig. 15.

The operation, uses and advantages of the invention just described are as follows:

If we assume use of the machine illustrated in Figs. 1 and 2, the bins are filled with stacks of paper 11, 12 and 13, which ordinarily are of different colors. The arrangement shown will provide for a book in which there is one original sheet and two copies or duplicates. Ordinarily, such a book contains carbon paper so that marks made upon the top sheet will be reproduced on two other sheets. It is here desired to manifold an original and two copies and to provide a plurality of such sheets in the order stated. When motor 22 is in operation the vacuum pump 49 is actuated and the shaft 19 is turned, which will rotate the cams 20 and 21. The pairs of feed conveyor belts 68 and 69 will be moved, as will likewise the belts 91 and 94, by the flexible drive 134. In addition, the belts shown at 109 and 110 will be in motion. As shaft 19 revolves, the cam 20 will raise and lower the elevator bar 27, to bring the suction feet 41 into engagement with the outermost sheet of the stack of sheets in each bin. During such movement of the suction feet the pump 49 is creating reduced pressure in the line 45 leading to said vacuum feet. During rotation of shaft 19 the cam 21 is rotated, and the construction of the cam is such as to cause movement of the conveyor belt frame 50 by reason of the lever arm 72 so as to bring the frame 50 forwardly toward the stock bins to position the pairs of conveyor belts adjacent each sheet raised by the suction feet to the position illustrated in Figs. 3 and 7. When the frame is moved to a position adjacent the bins, the said frame, through the medium of the adjustable screw 159 strikes part 154 of lever arm 152 and lifts the plug 155 from its seat, 75 breaking the vacuum to said vacuum feet, which

of course releases the paper from the vacuum feet and allows said paper to be received between the conveyor belts. The frame immediately commences movement away from the stock bins and the paper is passed under the chutes 34, between the belts 91 and 92 and directed beneath the belts 109 and 110. This assures that the sheets will be directed against one end of the receiving bin 35. In the meantime, due to the motion of frame 50, the ends 122 of arms 120 are engaged, which rocks the pairs of "joggers" 114 to align the sides of the sheets within the receiving bin.

If one or more of the suction feet fails for some reason to lift a sheet of paper so that manifolding would not proceed properly, then the vacuum actuated electrical switch illustrated in Fig. 10 would stop reciprocation of frame 50, and the vacuum to all of the vacuum feet would be broken and prevent delivery of incomplete sets of sheets to the receiving bin. It is evident that when a vacuum is created in the line 45 leading to the suction feet that plug 140 is drawn inwardly so that the head 142 of said plug is moved away from the contact arm portion 138. It is to be remembered that the circuit is such that lead 144 is in circuit with the disc 161 shown in Fig. 18. The timing is such that the metal segment 163 completes the electrical circuit leading to the various switches of the series of vacuum feet just after the vacuum feet have moved into contact with the uppermost sheets in the supply bins to thereby move the vacuum actuated plug 140 away from the contact arm 135, and each stud 140 will remain out of contact with said arm as long as the suction feet hold a sheet of paper. The disc 161 continues to turn and the brush or wheel 164 moves off the segment 163 at the moment the vacuum is broken to the vacuum feet, for at this time said sheets are received between the pairs of conveyor belts. This electrical circuit as just described is important, for the reason that unless it is made and broken properly the magnetic switch 81 will be actuated to release the frame from the lock bar 13, which would stop operation of frame 50. Switch 81 is only operated when, due to some defect in the manifolding operation, a vacuum foot does not properly lift a sheet or drops a sheet. If a vacuum foot drops a sheet, the plug 140 immediately engages contact 138 under urgency of the spring 143, and an electrical circuit is established through segment 163, brush 164 to switch 31, which lifts the plunger 32 from notch 80 and under urgency of springs 83, the frame 50 remains away from the supply bins. Thus the shaft 19 may continue to rotate but movement of arm 72 produces no movement in the conveyor frame 50.

The divider sheet mechanism is set by moving arm 170 to a desired graduation. After a number of sheets have been manifolded a divider sheet will be lifted from the bin and deposited within the receiving bin. If we assume that twelve sets of manifolded sheets are to be deposited within the bin 95 prior to placing a divider sheet thereover, the arm 170 would be moved to the indication marked "12", the parts of said mechanism would be in the position shown in Fig. 15. The pawl 176 is moved each time the frame 50 makes one complete reciprocation, the part 175 striking the bell crank 174, which through the linkage 172 moves the pawl carrying arm 171 downwardly.

Viewing Fig. 15, the pin 169 strikes the end

192 of lever 189 and moves lever 185 to the right to compress spring 198. The tripping element 187 of lever 185 will thereby be separated from tripping element 188 of lever 183, due to the fact that lever 183 is urged upwardly by coil spring 184. Thus the tripping element 188 will lie beneath the tripping element 187, and lever 193 will move counterclockwise to permit a moving of valve 203 from its seat 204. The pawl 176 is actuated each time the frame 50 makes a complete reciprocation. The lever 183 acts as a retaining or holding pawl for the ratchet wheel 165, as end 212 engages a tooth at a time to hold the ratchet wheel against retrograde movement. As the ratchet wheel turns, the pre-selector lever 178 will be brought into contact with holding pawl or lever 183, moving the same downwardly against spring 184. This releases end 212 from holding engagement with a tooth of the ratchet wheel. However, as the lever engages part 195, lever 193 is moved to close valve 203 to its seat 204 and thereby establish a vacuum connection from the pump to the vacuum feet through leads 207 and 208. As the shaft of the ratchet wheel 165 is spring loaded, the moment the holding pawl is moved from tooth engagement, the wheel will rotate counterclockwise until the pin 169 strikes the end 192 of lever 189 to move lever 185 clockwise against spring 198. Such movement releases the latching elements 187 and 188 so that part 188 now lies beneath part 187, with the result that arm 193 revolves counterclockwise to release the valve 203 from its seat 204, the lever 183 being actuated to bring the end 212 again into contact with the ratchet wheel teeth, under urgency of spring 184. It is evident that during the operation just set forth for the holding pawl and associated levers that the feed pawl 176 is out of contact with the teeth of the ratchet wheel, for the reason that the upper end of said feed pawl strikes a fixed arm 230. The action is then repeated, it being noted that when the arm 170 strikes the holding pawl 183 to move the same downwardly, the part 188 moves from beneath part 187 to the top thereof so as to hold said pawl out of engagement with the teeth of the ratchet wheel until the ratchet wheel is moved back to its preselected position.

The differential pressure arrangement for the valve 199 is such that the valve remains closed momentarily although the lever 193 is moved from valve engagement. When the line is atmospherized or the vacuum broken, due to the movement of the carriage 50, the valve 203 drops from the seat under gravity.

I claim:

1. In a collator, a supporting frame, a plurality of bins secured to said supporting frame and arranged at different elevations one above the other, a feed conveyor frame mounted for reciprocation on said supporting frame, pairs of continuous belts the faces of the belts in each pair being contiguous carried by said feed conveyor frame, and means for separating and raising the uppermost sheet in each bin and for releasing said sheets when said feed conveyor frame advances to position ends of said pairs of continuous belts adjacent the bins, the said raised sheets being received between said pairs of belts.

2. In a collator, a stationary supporting frame, a rotary feed conveyor mounted for reciprocation on said frame, an elevator bar and means for raising and lowering said bar; said bar provided with spaced apart suction feet, a plurality

of bins spacedly arranged one above the other and adapted to hold sheets of paper to be manifolded, the said suction feet overlying the uppermost sheets in said bins; pump means for effecting sub-atmospheric pressure to said suction feet when said elevator bar is lowered to position said suction feet over the uppermost sheet in each bin and to separate and raise said uppermost sheets when the elevator bar is raised; means for advancing the feed conveyor toward the sheets elevated by said suction feet to receive said sheets and for retracting the conveyor a distance less than the length of the sheets to be manifolded, and means actuated by the forward movement of said feed conveyor to atmospherize said suction feet when the said sheets are engaged by said feed conveyor.

3. In a collator, a plurality of bins arranged one above the other in spaced relationship, adapted to hold paper, suction feet for separating and raising the uppermost sheet from each bin and sub-atmospheric means leading to said suction feet, a vacuum operated electric switch carried by one of the suction feet for each bin, a feed conveyor for receiving sheets raised by said suction feet from each bin, means for advancing said feed conveyor toward the raised sheets in each bin, and for receiving the raised sheets, an electrical switch between said feed conveyor and said last named means, and electrical connections between said vacuum operated electric switches on said suction feet and said electrical switch on said feed conveyor, adapted to operate the conveyor switch and stop movement of said feed conveyor toward said bins in the event that one of said vacuum feet does not lift a sheet of paper from a bin.

4. In a collator, a vacuum foot adapted to be lowered upon a stack of paper sheets and raised thereabove, means for effecting a sub-atmospheric pressure to said foot whereby the foot may separate and raise the uppermost sheet from a stack, and for atmospherizing the foot to release a sheet, a vacuum operated electrical switch carried by said foot, comprising a movable contact and a fixed contact, said movable contact normally being in engagement with said fixed contact when the foot is atmospherized and for moving the said movable contact from said fixed contact when the foot is under sub-atmospheric pressure.

5. In a collator, a shaft, means for rotating said shaft, two cams mounted on said shaft, a bar in contact with one of said cams, suction feet carried by said bar, the said cam for said bar raising and lowering the bar during rotation of the cam to effect up and down movement of said suction feet, a plurality of bins arranged one above the other and adapted to hold sheets of

paper to be manifolded, the said vacuum feet positioned inwardly from one edge of each bin and directly above the uppermost sheets, a conveyor frame and means between said conveyor frame and the second cam adapted to reciprocate the conveyor means toward and away from each bin when said second cam is rotated; means for effecting sub-atmospheric pressure to said suction feet during the lowering of said suction feet for contact with the uppermost sheets in said bins to separate and raise said sheets, and means actuated by the conveyor means when the conveyor means is positioned adjacent the raised sheets to effect release of said sheets from the suction feet.

6. In a collator, a pair of cams, means effecting rotation thereof, a bar in contact with one of said cams, suction feet carried by said bar, the said cam for said bar raising and lowering the bar during rotation of the cam to effect up and down movement of said suction feet, a plurality of bins arranged one above the other, and adapted to hold sheets of paper to be manifolded, the said suction feet being positioned inwardly from one end of each bin and directly above the uppermost sheet, a conveyor frame and means between said conveyor frame and the second of said cams adapted to reciprocate the conveyor frame toward and away from each bin a distance less than the length of the sheet to be manifolded; a vacuum operated electrical switch carried by one of the suction feet for each bin, a conveyor drive control solenoid between said feed conveyor and said means for reciprocating the conveyor, electrical connections between each vacuum operated electrical switch and said conveyor drive control solenoid; said electrical switches on said suction feet closing the electrical path to the conveyor drive control solenoid in the event a suction foot does not lift a sheet to actuate said solenoid and stop the reciprocation of said conveyor means.
